UNITED STATES PATENT OFFICE.

ARTHUR D. CHILDERHOSE, OF OTTAWA, ONTARIO, CANADA.

DESIGN FOR A COTTON-RECEIVER.

46,982.

Specification for Design.

Patented Feb. 16, 1915.

Application filed February 12, 1914. Serial No. 818,420. Term of patent 14 years.

To all whom it may concern:

Be it known that I, ARTHUR D. CHILDERHOSE, a subject of the King of Great Britain, residing at 71½ Sparks street, Ottawa, in the Province of Ontario, Canada, have invented a new, original, and ornamental Design for Cotton-receivers, of which the following is a specification, reference being had to the accompanying drawing, forming a part thereof.

I claim:—

The ornamental design for a cotton receiver, as shown.

ARTHUR D. CHILDERHOSE.

Witnesses:

I. P. EBBS,
BELLE FRASER.
